US0D1107357S

(12) **United States Design Patent** (10) Patent No.: **US D1,107,357 S**
(45) Date of Patent: ** Dec. 23, 2025

(54) **VACUUM CLEANER**

(71) Applicant: **GUANGDONG DEERMA HEALTH TECHNOLOGY CO., LTD.**, Foshan (CN)

(72) Inventors: **Zijian Bu**, Guangdong (CN); **Long Chen**, Guangdong (CN)

(**) Term: **15 Years**

(21) Appl. No.: **35/521,725**

(22) Filed: **Jun. 28, 2024**

(80) **Hague Agreement Data**

Int. Filing Date: **Jun. 28, 2024**

Int. Reg. No.: **DM/238360**

Int. Reg. Date: **Jun. 28, 2024**

Int. Reg. Pub. Date: **Jul. 19, 2024**

(30) **Foreign Application Priority Data**

May 14, 2024 (CN) 202430284848.6

(51) **LOC (15) Cl.** **15-05**

(52) **U.S. Cl.**

USPC **D32/22**
